INVENTOR
CHARLES H. BROWN
BY *Minneapolis*
ATTORNEY

UNITED STATES PATENT OFFICE

CHARLES HENRY BROWN, OF BRECKENRIDGE, TEXAS

ROD GUIDE

Application filed July 5, 1928. Serial No. 290,620.

This invention relates to a device for maintaining the vertical position of reciprocating rods.

An object of the invention is the provision of a device for maintaining a polish rod of an oil well pump jack in true vertical plane alignment with the usual stuffing box while providing for a maximum stroke for the production of the greatest quantity of oil pumped at each stroke, with the least sucker rod trouble and with a minimum of wear on the polish rods and stuffing box.

Another object of the invention is the provision of a device which may be applied directly to any ordinary beam type pump jack or to any design of walking beam of standard oil rigs, such beams being usually left in position on finishing deep wells for the purpose of permitting cleaning or fishing.

A further object of the invention is the provision of a device for reciprocating rods while maintaining said rods in a vertical position, the device being of such adaptable construction that it may be readily fitted to walking beams of well-known designs in accordance with instructions disclosed by a template because of the fact that all of the elements composing the device have certain fixed dimensions relative to the length of the walking beams and are adapted to be employed in fixed positions relative to the horizontal line passing through the pivotal center of the beam.

This invention will be best understood from a consideration of the following detailed description, in connection with the accompanying drawings, nevertheless, it is to be understood that the invention is not confined to the disclosure being susceptible of such changes and modifications as shall define no material departure from the salient features of the invention as expressed in the appended claims.

In the drawings:—

Figure 1 is a view in elevation of an oil well pump showing my invention applied thereto,

Figure 2 is a fragmentary side view of the pump showing my invention in one position,

Figure 3 is a side view of a modified form

of the invention and in a different position from that shown in Fig. 2.

Figure 4 is an end view of the device shown in Fig. 2,

Figure 5 is a view in perspective of the link employed in Figs. 1 and 2.

Referring more particularly to the drawings 10 designates a Samson post upon which a walking beam 11 is pivotally mounted at 12. The post is braced by the members 13. 60 A headache post 14 spaced from the Samson post 10 and is braced and connected to the post 10 by means of a bar 15. A bull wheel 16 is provided with a crank 17. A link 18 connects the crank 17 with one end of the walking beam 11.

A link 20 is provided with a yoke 21 which is pivoted at 22 on a bracket 23 secured to the headache post 14. The opposite end of the link 20 is provided with a yoke 24 and a pivot pin 25.

A lever 26 is pivoted at 27 intermediate its ends on a bracket 28. One end of the lever is pivotally connected to the pin 25. The opposite end of the lever is curved or offset from the plane of the body of the lever, as shown at 29 and has pivotal connections at 30 with a reciprocating rod 31 which may be either a polish rod or a rod which connects a walking beam with a pumpjack. The lever 26, it will 80 be noted, has the lower portion 32 of a greater length than the upper portion 33. The portion 32 is located below the pivot point 27 and depends from the bracket 28.

The bracket consists of a vertically disposed arm 35 and an angularly disposed arm 36 which are connected together at their lower ends at the pivot 27. The upper ends of the arms diverge and are connected by means of bolts 37 to the extreme end of the walking beam 11. The bracket 28 consists of a pair of members similarly constructed and secured to opposite sides of the beam. The polish rod 31 is reciprocated in a stuffing box 38.

In the modified form of the invention shown in Fig. 3, the link 40 is provided with a longitudinal slot 41 which embraces opposite sides of the headache post 42. The link 40 is pivoted at 43 on a plate 44 which is 100

bolted at 45 to the brace rod 15^a. The operation of the modified form shown in Fig. 3, is identical with that shown in Figs. 1 and 2.

As the beam 11 is rocked, the polish rod 31 is moved in a vertical direction and in the same plane so that it will be held in vertical alinement with the stuffing box 38. As one end of the beam is elevated, the lever 26 is elevated as is the outer end of the link 20. 10 However, the variation in the relative positions of the link 20 and the lever 26 provides for maintaining the pivot point 30 at the upper end of the lever in the same vertical plane throughout the up and down movement of the end of the beam 11. This is due to the fact that the bracket 28 suspends the pivot point 27 of the lever 26 below the free end of the walking beam 11 in conjunction with the position of the pivot point 27 15 nearer to the upper end of the lever than to the lower end. Furthermore, the fact that the upper end of the lever is curved outwardly, as shown at 29, such curvature or displacement of the end will also aid in maintaining the proper alinement of the rod 31 20 during reciprocation.

I claim:

1. A device of the character described comprising a walking beam, a bracket depending from one end of said beam, a lever pivoted intermediate the ends thereof on the free end of said bracket, a post, a link having pivotal connection with the post and with one end of said lever, the other end of the lever being offset from the body of the lever, and a reciprocating rod having one end pivotally connected with the offset end of the lever, the greater portion of the lever depending below the pivotal point of said lever with the bracket.
2. A device of the character described comprising a walking beam, a bracket depending from one end of said beam, a lever pivoted intermediate the ends thereof on the free end of said bracket, a post, a link having pivotal connection with the post and with one end of said lever, the other end of the lever being offset from the body of the lever, and a reciprocating rod having one end pivotally connected with the offset end of the lever, the pivotal point of the lever being at one side of the center of the lever, the upper free end of the lever where connected to the reciprocating rod being normally located to one side of the pivotal point of the lever which is adjacent the free end of the walking beam.

Signed at Breckenridge in the county of Stephens and State of Texas this 29 day of June, A. D. 1928.

CHARLES H. BROWN.
